UNITED STATES PATENT OFFICE.

PETER J. CHRISTMAN, JR., OF GREEN BAY, WISCONSIN.

INTERFOLDING MACHINE.

Application filed May 17, 1921. Serial No. 470,398.

To all whom it may concern:

Be it known that I, PETER J. CHRISTMAN, Jr., a citizen of the United States, and resident of Green Bay, in the county of Brown 5 and State of Wisconsin, have invented certain new and useful Improvements in Inter-folding Machines; and I do hereby declare that the following is a full, clear, and exact description thereof.

- 10 My invention relates to improvements in folding machines, and particularly to that type of machine for folding sheets of paper in such a manner as to form packages, such as towels, toilet paper and the like.
- 15 The object of my invention is to provide a machine adapted to produce packs of folded sheets, the same being so arranged that when one of the lower sheets is removed from the pack end the free edge of the next 20 succeeding sheet is exposed, so that it may be readily withdrawn in a manner similar to that of the first. Such packs of folded sheets are customarily retained in a box having a slot in its bottom portion through 25 which projects the open edge of the lower sheet, so as to permit the removal of that sheet and the remaining sheets one after another in a manner similar to that described above.
- 30 A further object of my invention resides in the means for gripping the paper and moving it down upon the arc of a circle so as to maintain the proper distance or width of fold and pulling down during its 35 movement a sufficient quantity of paper for this purpose.
- A further object of my invention is to provide a machine of the character described, whereby the paper as it is fed to the folding 40 mechanism in a plurality of webs, is perforated at the proper interval, the paper then being trained around certain elements in such a manner that the perforations in one web lie within the 'central' portion of 45 the corresponding sheet in the second web. The sheets are connected in each web by unperforated portions which are adapted to be broken during the tucking operation of the inter-folding mechanism.
- 50 A further object is the utilization of a spring upon the gripping jaws, adapted to function when said spring is under tension and compression to close and open the jaws of the grippers, respectively.

Heretofore it has been a common fault in 55 machines of the character described for the paper to buckle during its folding operation, thus causing serious delays and loss of time in the operation of the machine. Therefore one of the salient points of my invention resides in the provision of folding means 60 whereby the paper during its folding operation is held taut by the gripping arms.

In the accompanying drawings:

Figure 1 is a side elevation of the complete machine, the top portion of which has mounted therein the perforating and guiding rolls, while the bottom portion carries the inter-folding mechanism.

Figure 2 is a front view of a portion of 70 the machine, showing the same partly in elevation and partly in section,

Figure 3 is a vertical sectional view taken through the end plate, and showing therein the manner of connections on the operating 75 shafts,

Figure 4 is a view showing in vertical section the gripping jaws and tucking arms in their several positions,

Figure 5 is a perspective view of one of 80 the gripping jaws and the tucking bar associated therewith,

Figure 6 is an end elevation of the gripping jaws and the tucker bar, illustrating the paper being forced between the jaws by the 85 latter and the manner of breaking the toggle on the jaws.

Figure 7 is a sectional view through the operating means of the jaws.

Figure 8 is a top plan view of one of the 90 gripping jaws and its operating element,

Figure 9 is a view illustrating diagrammatically the arrangement of the perforating and guide rolls.

Referring to the drawings in detail the 95 numeral 1 designates the main frame of my improved inter-folding machine, the same serving as a suitable support for the guiding and cutting rolls employed in the operation of the same. Referring to Figure 1, 100 it will be noted that the upper part of the frame carries the cutting and guiding rolls, while the lower part has mounted therein the various elements for inter-folding the paper. As disclosed in Figure 1, each side 105 of the main frame has detachably mounted therein a plate 2, having in its central portion an arcuate slot 3 through which pro-

jects the ends of the shafts carrying the gripping jaws, and which will be more fully described hereinafter. Furthermore, it will be noted that the extreme portions or ends of this slot are practically straight, while its apex is slightly curved, the reason of which being as the arms or shafts move down they are drawn away from the pack of folded paper. The same will be more clearly understood as the description proceeds.

Each plate 2 has arranged within its central portion a bearing, having mounted therein a stub shaft 4 adapted for oscillation, the same having keyed thereto an arm 5, the free end of which has pivotally connected thereto the pitman 6, the other end of which is connected to a correspondingly formed arm 7 secured upon the end of one of the guiding or cutting rolls in the upper part of the main frame. By this arrangement, it will be noted that as the rolls in the upper part of the machine receive the initial power the same will be transmitted to the shaft 4 by means of the pitman 25 and connections just described.

Extending transversely of the main frame and positioned somewhat below and on each side of the stub shaft 4 are shafts 8 and 9 mounted in such a manner that they may be freely oscillated to permit the operation of the tucker bars, which will be more fully described hereinafter, carried thereby within the interior of the machine.

Referring to Figures 3 and 4, it will be noted that the shaft 4 has keyed thereto, adjacent its end and within the interior of the machine a sleeve 10, the same having made integral therewith a pair of arms 11 and 12 positioned at right angles to each other with respect to the axis of the sleeve. The free ends of the arms are provided with substantially U-shaped yokes 13 which are adapted to receive therein grooved rollers 14, which are loosely mounted on the shafts 15 and 16 extending transversely of the machine. The end portions of these shafts pass through the slots 3 in the side plates 2, the shafts being further provided with rollers 17 loosely mounted thereon and adapted to engage that portion of the plates 2 which form the slots 3.

The rollers 14 and 17 are held in spaced relation with respect to each other and in their proper operating positions on the shafts 15 and 16 by suitable washers or collars 18. The end portions of each shaft or that portion which protrudes beyond the outer side of the plates 2 have keyed thereto sleeves 15', the same further serving to hold the various rollers and elements carried by the shafts in their proper functioning positions.

Each shaft 8 and 9 previously referred to has keyed thereto and adapted to oscillate therewith a pair of curved arms 19 and 20,

respectively, each pair being keyed to its shaft in horizontal alignment, and each oppositely disposed arm in each pair also being keyed in transverse alignment. The upper ends of each pair have detachably connected thereto the transversely extending bar 21, which I shall hereinafter refer to as the tucker bar.

Each pair of oppositely disposed arms, those indicated in Figure 4, are normally urged toward each other by means of the tension spring 22, the free ends of which are connected to plates 23 and 24 pivotally mounted on each arm adjacent its connection with the shafts 8 and 9, and one of the arms or plates, as indicated at 25, may be provided with means for regulating the required tension of the spring. The shafts 15 and 16 are provided with paper-gripping jaws, the purpose of which broadly speaking, is to grasp the paper and move it down in an arc, and during its movement form the fold for the paper, each jaw alternately gripping a portion of the paper. Referring to the structure of the jaws in detail, and particularly to Figure 4, it will be noted that each jaw is composed of an upper jaw 26 and a lower jaw 27, the main portion of each being concaved longitudinally of its length, and on adjacent faces to receive therein and between the two jaws the shafts 15 and 16, but that portion of each jaw which remains on each side of the concaved portion being inclined upwardly and downwardly of the upper and lower jaws respectively, the purpose of which being to permit the free oscillation of each jaw upon the shaft. In order that the two jaw sections may be snugly and yet movably held upon their carrying shaft, we have arranged upon the end face of each jaw an annular extension or boss 28, the same being formed by cutting the jaw end back, as indicated in Figure 8, so that a collar 29 may embrace the extensions 28, and at the same time be freely rotatable thereon.

By referring to Figure 3, it will be noted that the collar not only serves as the means for holding the jaws upon the shafts 15 and 16, but functions as a roller which is adapted to engage the inner face of the arms of the coacting tucker bars 19 and 20, and adapted to oscillate the same upon their pivots during the downward and upward movement of each shaft.

As shown in the drawings, each jaw is provided with a removable end or tip 30, the same being made of some suitable fiber which has a greater coefficient of friction than the jaw itself, the purpose of which is to provide comparatively resilient gripping points at the end of the jaw members. The jaw tips extend the full length of each jaw and is held thereto by threaded screws adapted to engage the threaded openings 31

- in the jaw edge. Each jaw member is further provided with vertically aligned slots 32, through which pass the vertically extending paper holding arms 33' arranged 5 to hold the paper at both sides of its folded edges, the same being arranged in pairs and in spaced relation to each other transversely of the machine, and being held in their respective positions by suitable rods passing 10 therethrough. The upper end of each bar or arm 33' is provided with a rack face to prevent the upward movement of the paper after it is forced down by the upper nose of the jaw 26. As further shown the end portion 15 of the notched section of the arm 33' is provided with a needle which also serves to hold the paper down more securely. Each paper gripping jaw 26 and 27 is cut away to permit the connection to its carrying 20 shaft of the means for controlling the gripping action of the jaws. A portion of the shafts 15 and 16 which becomes exposed by reason of the cut out portions of the jaws is provided with flat diametrically opposite 25 faces upon which is arranged for transversely sliding movement with respect to the shaft a head 33 having secured thereto a rod 34, the other end of which is slidably mounted within a sleeve 35 made integral 30 with the U-shaped yoke 36, the legs of which are pivotally mounted on vertically extending girders 37 secured to the main frame of the machine. Interposed between the sleeve 35 and the head 33 and coiled about the rod 34 is a spring 38, the ends of which are connected to the head and sleeve, as indicated at 39 and 40. Each gripping jaw may be provided adjacent its end portion with one of such previously described controlling 40 means, or if occasion may demand a plurality of the same may be arranged throughout the longitudinal length of the jaws.
- The head 33 has arranged within its upper and lower portion, that portion which protrudes beyond the faces of jaws, and extending parallel with the jaw carrying shaft, oppositely disposed projecting pins 41 and 42. Arranged parallel with the faces of the head 33 are yoke members 43 and 44 disposed 45 on each side of the head, and having one end of each rigidly connected to the top and bottom jaw, respectively, while its free end is bifurcated and adapted to engage the projecting pins 41 and 42. By this arrangement, it will be noted that as the head 33 moves transversely of the shafts 15 or 16 by reason of the yoke members 43 and 44 the jaws will be caused to open or close, according to the movement of the head.
- 50 The end faces of the upper and lower jaws in each set have pivotally connected thereto a toggle member composed of the members 45 and 46, being pivotally connected, as at 47. The upper member adjacent its connection is provided with a squared surface, while the adjacent end on the lower member is provided with a rounded end, the purpose of which is to permit the toggle to be broken in one direction only. In order to break the toggle prior to their gripping 70 action on the paper, the tucker bar arm has provided thereon a sleeve 48 removably held within a socket portion formed on the upper face of the arm, said sleeve being internally threaded and adapted to receive therein a 75 threaded screw 49 which may be moved back and forth therein, so as to cause the breaking of the toggle at its correct position or moment. In order that the toggle may be held in such a position that the jaws are 80 held opened, we have provided on the upper face of the top jaw a spring 50, the free end of which engages the upwardly projecting part of one of the toggle members.
- 85 As disclosed in Figure 5, I have illustrated a modified form of the tucker bar, the same having the removable lip 51.
- 90 From the above description, it is thought that the operation of the machine, as a whole, will be fully understood, but in order that the operation may be clearly stated the same is as follows: Referring to Figure 4, it will be noted that the paper as it passes from the perforating and guiding rolls, is gripped by the jaws 26 and 27, the same being forced 95 therein by the tucker bar 21, and during its insertion the connecting strips of the sheets in one web are broken and its end portions being held by the gripping action of the jaws under the fold of the second web. As 100 the shaft 4 oscillates the shaft 15 is moved downwardly in the slot 3, and during this movement the spring 38 is compressed, which action causes the head 33 to slide transversely of the shaft 15, and by reason of the yoke 105 connections 43 and 44 with the jaws 26 and 27, the same are caused to open, but this action does not take place until the spring has passed its neutral position. It will be understood that in the upward position as 110 shown in Figure 4, the spring is under tension. As the jaw moves downward, and enters the straight portion of the slot the same is drawn away from the folded pack, and at the same time the jaws open sufficient, due to the forward movement of the head, to permit the paper to pass thereout, and during the continued movement of the jaws the long nose of the upper jaw 26 bears on the folded edge of the paper and 115 forces the same down under the rack face or the notched face of the arms 33'. In order that the jaws may be held opened at the termination of its downward movement and at the beginning of its downward movement, and to permit the insertion of the paper therebetween prior to the latter movement, the toggle arrangement is thrown automatically into action, when the jaws are forced opened by the forward movement of 120
- 125 60 65 70 75 80 85 90 95 100 105 110 115 120 125 130

the head, and remains so until the toggle is broken on the insertion of the paper by the bar 21. During the downward movement of the shaft 15 the roller 29 carried thereby strikes the coacting face of the arm 19, and moves the same into such a position that the tucker bar 21 of the arm 19 will be caused to insert the web of paper in the gripping jaws carried by the shaft 16. Thus it will be seen that while one set of jaws is discharging its paper the other set is receiving a new fold.

As shown in Figure 9, I have diametrically illustrated the arrangement of the guiding and perforating rolls, the same being so arranged as to perforate the two webs of paper together, and by an offset arrangement of the roll A the perforations in the web B are caused to strike the intermediate portion between the perforation in the web C when the same is carried back by the roll D. It is to be understood that this arrangement is mounted in the upper part of the machine and the power for actuating the same is received to one of the rolls in any suitable manner. The roll E as in apparent is provided with an adjustable cutting knife which coacts with slots arranged in the periphery of the drum F, this forming the perforations of the two webs simultaneously.

Referring to Figure 1, the shafts 8 and 9 which project beyond the exterior of the machine, have pivotally connected thereto pawls 52 and 53, the same engaging ratchet gears 54 and 55 keyed upon the shafts 56 and 57 which extend transversely of the machine. The shaft 56 has keyed thereto and held in spaced relation as indicated in Figure 2, a plurality of disks 59, the periphery 40 of which is adapted to engage the folded sheets of paper and roll the same out from between the lower ends of the paper holding arms 33, one of which terminates short of the curved end of the other, and upon a 45 endless conveyer 60 which passes around a suitable drum 61 arranged upon the shaft 57. By this arrangement, it will be apparent that as the shafts 8 and 9 are oscillated the endless conveyer and disks will be 50 intermittently moved by the action of the pawls.

From the foregoing, it is thought that the construction, operation and many advantages of the herein described invention will 55 be apparent to those skilled in the art, without further description, and it will be understood that various changes in the size, shape, proportion and minor details of construction, may be resorted to without departing from the spirit or sacrificing any of the advantages of the invention.

Having thus fully described my invention, what I claim as new, and desire to secure by Letters Patent is:—

65 1. A folding machine comprising two pair

of paper gripping jaws adapted to alternately receive therein paper webs and move outwardly upon the arc of a circle to fold the same, and spring controlled means connected to each jaw adapted to close and open 70 the same at certain periods within the limits of their movements.

2. A folding machine comprising two pair of paper grippers adapted to alternately receive therein paper webs and move outwardly upon the arc of a circle to fold the same, a sliding element carried by each gripper and having connections with the jaws of each gripper, and resilient means controlling the opening and closing action 80 of each gripper at certain periods within the limits of its movement.

3. A folding machine comprising a pair of arms moving in fixed relation, shafts carried by the arms and moving outwardly in 85 the arc of a circle, sets of gripping jaws carried by each shaft, means operated by the movement of one set of jaws for tucking paper into the other, and means within the jaw portions of each set and slidably transversely of the shafts for closing and opening the same during certain periods of their movements.

4. A folding machine comprising two sets of alternately actuated folding jaws, 95 adapted to grip sheets to be folded at approximately a common point, and means for imparting an initial outward arcuate feed movement to each jaw set followed by a further outwardly offset movement to thereby 100 cause the jaws to clear the stack of sheets previously interfolded.

5. A folding machine comprising two sets of alternately actuated folding jaws adapted to grip sheets to be folded from approximately a common point, means associated 105 with each set for gripping the sheet to be folded, and means associated with each set for causing the same to initially move outwardly in an arc of a circle followed by a further movement tangentially to the arc whereby the sheet carried by said jaw is disposed upon the previously folded stack and released.

6. A folding machine comprising two sets 115 of alternately actuated folding jaws adapted to grip sheets to be folded from approximately a common point, means associated with each set for gripping the sheet to be folded, means associated with each set for causing the same to initially move outwardly in an arc of a circle followed by a further movement tangentially to the arc whereby the sheet carried by said jaw is disposed upon the previously folded stack, and means for releasing said sheet at a determined point before same is deposited upon the previously folded stack.

7. A folding machine comprising two sets 120 of folding jaws adapted to move in fixed

relations, an extended nose on the upper jaw of each set, means for tucking paper into each jaw set successively, and means for releasing paper therefrom during the inter-
5 folding movement of the jaws.

8. A folding machine comprising two sets of folding jaws adapted to move in fixed relations, the upper jaw of each set being extended beyond its companion jaw of each
10 pair, means controlled by the movement of one set of jaws for tucking paper into the other set, and means for releasing the paper therefrom during the interfolding movement of the jaws.

15. 9. A folding machine comprising two sets of folding jaws adapted to move in fixed relation, an extended nose on the upper jaw of each set, means controlled by the movement of one set of jaws for tucking paper
20 into the other set, and means for opening and closing said jaws within the limits of their interfolding movement.

10. A folding machine comprising two sets of folding jaws, an extended nose on
25 the upper jaw of each set, said jaws adapted to oscillate in fixed relations, means for tucking paper into each set of jaws at the start of its interfolding movement and resiliently controlled means connected to each
30 set of jaws for opening and closing the same successively within the limits of their interfolding movement.

11. A folding machine comprising two sets of folding jaws adapted to move in
35 fixed relations, an extended nose on the upper portion jaw of each set, means for tucking the paper between the jaws of each set successively, and means for initially guiding said jaws outwardly on the arc of a circle

and then tangentially to the circle within 40 the limits of the interfolding movement.

12. A folding machine comprising a pair of folding arms which oscillate in fixed relations, said arms carrying two sets of gripping jaws, the upper portion jaw of each 45 set having an extended nose, means controlled by the movement of one jaw set for tucking paper into the other jaw set, means for guiding each jaw set partway in its outward and downward movement on the arc 50 of a circle and then tangentially to the circle to the the limit of the movement, and a resiliently controlled transverse sliding means connected to each jaw set for opening said jaws at a certain period within the 55 limit of its interfolding movement.

13. A folding machine comprising a pair of oscillating arms, moving in fixed relations, shafts carried by said arms, a set of gripping jaws carried by each shaft, an extended nose on the upper jaw of each set, means operated by the movement of one set of jaws for tucking paper into the other set, means for guiding said sets of jaws partway on the arc of a circle and then tangentially to the circle and resiliently controlled transverse sliding means for opening and closing gripping jaws at a certain period within the limit of its movement, and means for causing gripping jaws to turn 65 70 from an oblique position to a horizontal position and vice versa, during its arculatory folding movement.

In testimony that I claim the foregoing I have hereunto set my hand at Green Bay, 75 in the county of Brown and State of Wisconsin.

PETER J. CHRISTMAN, JR.
